UNITED STATES PATENT OFFICE.

WILLIAM ERASTUS RAYNOR, OF UTICA, NEW YORK, ASSIGNOR TO UNION SPECIAL MACHINE COMPANY, OF CHICAGO, ILLINOIS, A CORPORATION OF ILLINOIS.

TRIMMING MECHANISM FOR SEWING MACHINES.

Application filed July 17, 1918. Serial No. 245,272.

To all whom it may concern:

Be it known that I, WILLIAM E. RAYNOR, a citizen of the United States, residing at Utica, in the county of Oneida, State of New York, have invented certain new and useful Improvements in Trimming Mechanisms for Sewing Machines, of which the following is a description, reference being had to the accompanying drawing, and to the figures of reference marked thereon.

The invention relates to new and useful improvements in trimming mechanisms for sewing machines and more particularly to a trimming mechanism having a pair of co-operating toggle blades or members operating to sever the material by abrasion.

In the patent to Durand No. 698,912, granted April 29, 1902, a toggle trimming mechanism of the above type is shown and described and these toggle trimming members are so arranged as to swing together during their trimming action and the toggles are operated by the movements of the feed rocker. Necessarily all adjustments in the stroke of the feed bring about a corresponding adjustment in the stroke of the toggle members. Where the toggle members are connected by a projecting tooth carried by one member and meshing or engaging in a recess in the opposite toggle member, if the stroke of the toggle members is relatively long, there is a great deal of wear or pounding of the parts.

An object of the present invention is to provide means whereby toggle members of the character disclosed in the Durand patent may be operated from the feeding mechanism and in timing therewith, but wherein the stroke of the toggle members may be varied independently of the stroke of the feed dog, so that the range of movement of the toggle members may be adjusted so as to prevent resulting noise and wear incident to the striking of the parts one against the other.

In the drawings which show by way of illustration one embodiment of the invention:

Figure 1 is a vertical sectional view showing a portion of a sewing machine having my improvements embodied therein, the work support and the feed dog being indicated in dotted lines so as to clearly show their relation to the trimming members and the means for operating the same;

Fig. 2 is a front view of a portion of the forward end of a machine having my improvements embodied therein;

Fig. 3 is a view partly in plan and partly in horizontal section showing the trimming mechanism in top plan;

Fig. 4 is a sectional view on the line 4—4 of Fig. 3;

Fig. 5 is a detail showing the position of the toggle trimming members at the rear end of their stroke when the range of movement of the toggles is within proper limits;

Fig. 6 is a similar view but showing the toggles at the forward end of their stroke;

Fig. 7 is a similar view but showing the toggles at the rear end of their stroke when adjusted beyond the proper limit, which results in great wear on the parts; and

Fig. 8 is an end view showing the adjustable crank for operating the feed rocker.

In the patent to Durand referred to above, a toggle trimming mechanism is disclosed which includes co-operating trimming members which operate to sever the material by abrasion. These toggle trimming members are formed one with a projecting tooth and the other with a correspondingly shaped recess, so that the tooth meshing or engaging with the recess will cause all movements of one member to be imparted to the other. One of the toggle members is connected by a link to a bracket on the feed rocker, so that as the feed rocker oscillates to impart feeding movements to the feed dog, the toggles will be swung so as to co-operate in the severing of the material. The bracket in the Durand patent is fixed to the feed rocker and as a result all adjustments in the throw of the feed rocker which varies the stroke of the feed dog, will likewise vary the stroke of the toggle trimming members. If the throw of the toggle trimming members is beyond a certain limit, the tooth will be withdrawn from the co-operating recess to such an extent as to cause more or less of a striking of the parts when the parts are meshing, resulting in noise and wear of the parts.

The present invention is directed to an arrangement whereby the toggle trimming members may be operated from the feed rocker and whereby the feed rocker may be adjusted for any desired stroke of the feed dog and at the same time the throw of the toggle trimming members may be adjusted

so as to be within proper limits to avoid this undesirable noise and the wear incident to the striking of the parts one on the other.

- 5 Referring more in detail to the drawings, I have shown my invention as embodied in a trimming mechanism applied to a sewing machine having a needle bar 1, carrying a needle 2. Co-operating with the needle is 10 a looper 3. The material is fed across the work support by a feed dog 4. This feed dog is carried by a feed bar 5. The feed bar is pivoted at 6 to a feed rocker 7, which in turn is pivoted at 8 to the bed 9 of the machine. The feed bar is raised and lowered by an eccentric 10 on the main shaft 11. The feed rocker is vibrated back and forth by an arm 12 which is made as a part of the rocker and this arm is connected by a 15 link 13 to a crank 14 on the end of the main shaft. This crank 14 is carried by a disc 15 and is capable of radial adjustment across the disc so that the throw of the crank may be varied, which results in varying the 20 throw of the feed rocker. It will thus be seen that the stroke of the feed dog may be readily varied by shifting the position of the crank 14 on the disc 15.

The trimming mechanism includes two trimming members 16 and 17 and the member 16 is pivoted at 18 to a suitable bracket, while the member 17 is pivoted at 19 to this same bracket. The manner of mounting these toggle members may be similar to that shown in the patent referred to. The member 16 is provided with a projecting tooth 20 which is adapted to engage or mesh in a recess 21 formed in the member 17. The member 17 is pivotally connected at 22 to a link 23. This link 23 is fixed to a pin 24 by a screw 25 and the pin 24 is journaled in a bracket 26. The inner face of the feed rocker is formed with a seat 27 for the bracket 26. The feed rocker is also formed 25 with vertical slots 28. There is a screw 29 passing through each vertical slot into the bracket. By loosening these screws the bracket 26 may be raised and lowered vertically. It will be noted that when the bracket 26 is raised the pivot pin 24 is moved farther from the pivot point 8 of the feed rocker and on the other hand when the bracket is lowered, then this pivot pin 24 is brought nearer to the pivot point 8. Assuming that the feed rocker has a fixed throw, the adjustment of the bracket 26 upwardly will increase the throw of the pin 24 and the adjustment of the bracket 26 downwardly will decrease the throw of the pin 24 relative to this fixed throw of the feed rocker.

The position of the pin 24 is always slightly above the pivot point 8, at which the feed bar is connected to the feed rocker, so that the throw of the toggle trimming

members is slightly greater than that of the feed bar and the resulting distance which the fabric is moved. In Figure 5 of the drawings, I have shown the trimming members at the rear ends of their stroke and the trimming members are moving at the maximum throw thereof. In Figure 6 I have shown these trimming members at the forward end of their stroke. If the trimming members be moved rearwardly to a greater extent than that shown in Figure 5, the result indicated in Figure 7 is brought about. In this figure it will be noted that the tooth 20 is withdrawn from the recess 21 to such an extent that the outer surface 80 of the tooth is out of contact with the rear wall of the recess.

Under these conditions, as the toggle trimming members move back and forth there is more or less of a striking of the parts one against the other, resulting in noise and an undue wear of the parts on each other, due to pressure of upper toggle while under toggle is being driven, thus causing a relative sliding action until lost motion has been taken up. It is this sliding action which causes the upper toggle to "groove" the under toggle and thereby render the latter useless.

In this type of machine, it is often desirable to adjust the feed dog so as to have a relatively long feed stroke. It has been found that when the toggle members are operated from a point of connection with the feed rocker, that the maximum throw of the feed dog results in such a great throw of the toggle members as to cause unmeshing and striking of the parts and resulting noise and wear thereto. When the feed dog is adjusted for an extreme feed stroke as above noted, the bracket 26 is lowered so that the relative stroke of the toggle trimming members will be slightly less and well within the limits indicated in Figures 5 and 6 of the drawings. On the other hand, when the feeding mechanism is adjusted so that the stroke of the feed dog is relatively short, then the bracket 26 may be raised so as to increase the throw of the toggle trimming members to such an extent as to bring about efficient trimming of the material. It will readily be seen from the above that I have provided a mechanism for operating the toggle trimming members from the feed rocker, which includes features for varying the stroke of the toggle trimming members so that efficient trimming or severing of the fabric may be accomplished for all variations in the stroke of the feed dog and without any pounding of the parts one on the other with resulting wear and noise.

It is obvious that minor changes in the details of construction may be made without departing from the spirit of the invention, as set forth in the appended claims.

Having thus fully described my invention, what I claim as new and desire to secure by Letters Patent, is:—

1. The combination of a feeding mechanism including a feed dog, a feed bar supporting said feed dog, a feed rocker to which said feed bar is attached, means for vibrating said feed rocker, means for varying the throw of the feed rocker and a trimming mechanism including toggle trimming members, one of which is provided with a tooth engaging or meshing with a recess in the other toggle trimming member, a bracket adjustably connected to the feed rocker whereby it may be moved toward and from the pivot of the feed rocker and a link connecting said bracket with one of said toggle trimming members.
2. The combination of a feeding mechanism including a feed dog, a feed bar supporting the same, a pivoted feed rocker to which said feed bar is connected, means for vibrating the feed rocker, means whereby

the throw of the feed rocker may be varied and a trimming mechanism including toggle trimming members, one of which is provided with a tooth, the other with a recess with which said tooth meshes, the inner face of said feed rocker having a seat formed thereon provided with vertical slots, a bracket mounted on said seat, screws passing through the slots into the bracket, whereby the same is adjustably secured to the feed rocker, so that the bracket may be moved toward and from the pivot of the feed rocker, the upper end of said bracket being above the feed bar connection to the feed rocker and a link connected to the upper end of the bracket and to one of the toggle trimming members.

In testimony whereof, I affix my signature in the presence of two witnesses.

WILLIAM ERASTUS RAYNOR.
